MULTIPLE BORING MACHINE

John J. Croft, Sr., Siler City, N. C., assignor to
High Point Bending & Chair Company, Siler
City, N. C., a corporation of North Carolina

Application February 3, 1947, Serial No. 726,013

5 Claims. (Cl. 144—112)

1

This invention relates to an automatic machine, capable of performing various different operations upon various different pieces of work of various different materials, but more especially designed for performing boring, doweling, cutting-off and similar operations upon wooden elements such as legs, stretchers and the like from which chairs and other articles of furniture are constructed, and has for its general object to provide a simple, practical automatic machine to perform operations such as those mentioned and which heretofore have required the use of two or more separate machines, thereby materially to reduce production time and costs.

The present machine comprises a frame including a plurality of work-head supporting bars; means for fastening a piece of work to be operated upon, and a plurality of work heads mounted upon said bars for operation upon a piece of work fastened by said fastening means. Each work head includes a motor for driving a tool for operation upon the work and a guide element upon which said motor is mounted to slide to project and retract the tool relative to the work, and in this connection a special object of the invention is to construct each work-head so that the motor guide element, and hence the motor, may readily be adjusted along, rotatably about and laterally with respect to its supporting bar, as well as rotatably about an axis extending at right angles to the axis of its supporting bar, so as to position the tool in practically any desired attitude relative to the work for operation thereon.

Suitable yieldable means tends constantly to retract each motor; fluid-operated cylinder and piston means is provided to project each motor, and suitable valve means is provided for controlling supply of fluid under pressure to each cylinder and piston means and its exhaust therefrom so that the motors and the tools are projected and retracted at desired times, either simultaneously or in desired sequence, depending upon the particular operations being performed. In this connection it may be in some instances that the path of movement of a given motor may extend across the path of movement of another motor, or that some given motor might otherwise interfere with proper operation of another motor, if both motors were projected simultaneously. Accordingly, another special object of the invention is to provide valve means whereby the supply of fluid pressure to the cylinder and piston projecting means of any given motor may be positively denied until another possibly interfering

2

motor has been retracted so as to insure against any possible interference of projection of any given motor with projection of any other motor.

Another special and important object of the invention is to construct the work heads compactly and, at the same time, to provide simple, practical means for effecting and maintaining adjustments of the motor supporting guide elements.

10 With the foregoing and other objects in view, which will become more fully apparent as the nature of the invention is better understood, the same consists in an automatic machine embodying the novel features of construction, combination and arrangement of parts as will be hereinafter more fully described, illustrated in the accompanying drawings and defined in the appended claims.

20 In the accompanying drawings, wherein like characters of reference denote corresponding parts in the different views:

Fig. 1 is a front elevation of an automatic machine constructed in accordance with one practical embodiment of the invention.

Fig. 2 is a top plan view of the machine.

Fig. 3 is a cross sectional view through the machine taken approximately on the line 3—3 of Fig. 1.

Fig. 4 is an enlarged view, partly in side elevation and partly in section, of one of the work heads.

Fig. 5 is a front elevation of the work head shown in Fig. 4.

Fig. 6 is a top plan view of the work head shown in Fig. 4.

Fig. 7 is a view similar to Fig. 4 looking toward the opposite side of the work head.

Fig. 8 is a section on the line 8—8 of Fig. 4.

Fig. 9 (Sheet 2) is a section on the line 9—9 of Fig. 4.

Fig. 10 is a section on the line 10—10 of Fig. 4; and

Fig. 11 is a detail view illustrating valve means operable by projection and retraction of the motor of one work head to control supply of fluid to the cylinder and piston projecting means of another work head.

Referring to the drawings in detail, A designates generally the frame of the present machine which may be of any suitable construction and which is illustrated in the present instance as comprising a pair of end plates 10, 10 connected together near their tops by a plurality of work head supporting bars 11 and near their bottoms by a plurality of stay bars 12.

The number of the work head supporting bars 11 and their arrangement relative to each other is arbitrary. For practical purposes, however, there may be upper and lower, forwardly and rearwardly spaced apart pairs of these bars, the lower pair of which may be somewhat more widely spaced apart than the upper pair, as shown. In addition, either or both pairs of said bars 11 may support one or more forwardly and rearwardly extending work-head supporting bars 13. The work-head supporting bars themselves as well as the stay bars 12 preferably are of tubular form, as shown, so as to combine lightness in weight with rigidity and strength.

The work-heads are designated generally as B and their number, as well as their disposition relative to each other and with respect to their supporting bars, is arbitrary, depending upon the particular operations to be performed.

Any suitable means may be provided for fastening a piece of work to be operated upon by the work-heads B. Preferably, however, the work fastening means comprises duplicate units, designated generally as C, any desired number of which may be employed in any given instance and which are designed to be mounted upon the upper pair of the bars 11, for example, in desired spaced apart relationship to each other, depending upon the particular size and shape of a piece of work to be fastened.

Each unit C may comprise, as shown, a bar 14 extending forwardly and rearwardly across the space between the upper pair of the bars 11 and provided at its ends with suitable bar 14 embracing and clamping means 15 whereby it may be secured rigidly to said bars 11 in any desired position of adjustment therewith.

Mounted upon the bar 14 for sliding adjustment forwardly and rearwardly therewith is a work-piece rest 16 which is provided with a set screw 17 for engagement with the bar 14 to secure said rest in a desired position of adjustment along said bar, while rising from said rest is a standard 18 upon which is suitably mounted for vertical adjustment relative thereto a cylinder 19 which overlies the rest 16.

In the cylinder 19 is a piston 20 having a piston rod 21 which extends through the lower end of said cylinder and which is provided at its lower end with a suitable foot piece 22 to engage the top of a piece of work *a* resting upon the rest 16 and to clamp it against said rest when air or other fluid under pressure is admitted to the top of the cylinder 19 to urge the piston 20 downwardly. Suitable spring means, such as is indicated at 23, is provided to raise the piston 20 and the foot piece 22 to release the work-piece *a* when the upper end of the cylinder 19 is relieved of fluid pressure.

Each work head B comprises a guide element 24 upon which a motor 25 may be slidably mounted in any suitable manner for projection and retraction to project and retract a tool 26, driven by the motor, to and from a position to perform its operation upon a piece of work *a* fastened by the units C. In this connection and as illustrated in the present instance, the guide element 24 is provided at its rear side with a channel 27 (Figures 4 and 6) of dove-tail shape in cross section and the motor 25 is provided with a base 28 of dove-tail shape in cross section disposed in said channel, whereby the motor is maintained operatively engaged with said guide element and yet is projectable and retractable relative thereto.

In accordance with known practice, tool heads

29 for tools of different kinds may be interchangeably mounted on any given motor 25 so that any such motor may be employed to drive any given tool or tools 26, as, for example, a circular cut-off saw, a dowel-forming chuck, or one or more drills or bits.

For projecting the motor 25 and its tool, a cylinder and piston unit 30 comprising a cylinder 31 and a piston 32 is employed. The cylinder 31 is mounted on the guide element 24 behind the motor 25 and the piston 32 has extending therefrom a piston rod 33 which is engaged with the rear end of the motor. Consequently, by admitting air or other fluid under pressure to the rear end of the cylinder 31, the piston and the piston rod are moved to project the motor. On the other hand, suitable spring means, as indicated at 34, is provided to retract the motor and to hold it retracted whenever the rear end of the cylinder 31 is relieved of fluid pressure.

The cylinder and piston unit 30 constitutes a stop to limit retractive movement of the motor 25, and since the motor always is projected the same amount when fluid pressure is admitted to the rear end of the cylinder 31, it is desirable to provide for adjustment of said cylinder and piston unit longitudinally relative to the guide element 24 to variably predetermine the retracted position of the motor 25 relative to said guide element to adapt the tool driven by the motor to be projected the proper amount relative to any given piece of work fastened by the work fastening units B. To this end the cylinder 31 may be provided with a base 35 of dove-tail shape in cross section engaged in the channel 27 of the guide element 24 to slidably mount said cylinder on said guide element, and said guide element may carry a screw 36 swiveled with respect thereto and in threaded engagement with said base 35 so that by rotating said screw the cylinder and piston unit 30 may be adjusted to any desired position longitudinally with respect to said guide element 24.

Rigid with the guide element 24 and extending forwardly therefrom at right angles thereto is an arm 37 of cylindrical shape in cross section which fits neatly within a cylindrical bore 38 in a housing 39 carried rigidly by a bracket 40.

The bracket 40 is composed of half sections 41 and 42 which embrace the supporting bar 11 upon which the work head is mounted, and said half sections are hinged together at one side of the bracket, as indicated at 43, and are connected together at the other side of the bracket by a clamp screw 44, whereby they may be released to permit rotative and longitudinal adjustments of the bracket relative to the supporting bar 11 and may be drawn together to clamp the bracket upon said bar in any desired position of adjustment of the bracket along and rotatively with respect to said bar.

The housing 39 extends at right angles to the bar 11 and has swiveled in the front end thereof a screw 45 which extends axially relative to said housing and is in threaded engagement with the arm 37. Accordingly, by rotatably adjusting said screw 45, the arm 37 and, consequently, the guide element 24 may be adjusted laterally relative to the supporting bar 11.

On the arm 37 and keyed thereto, as indicated at 46, is a worm wheel 47 which is housed by the bracket 40 and which has engaged therewith a worm 48 which is suitably mounted in said bracket. Accordingly, by rotating said

worm, said worm wheel may be rotated to rotatably adjust the arm 37 and the guide element 24 carried thereby.

A portion of the housing 40 is formed as a tongue 49 of limited circumferential extent having a free end 59 through which a clamp screw 51 extends loosely and is threaded into the bracket 40. This clamp screw is loosened whenever it is desired to rotatably or longitudinally adjust the arm 37 and is tightened to draw the tongue 49 into clamping engagement with said arm to maintain the latter in any position to which it may be adjusted.

Keyed on the supporting bar 11, as indicated at 52, whereby it may slide longitudinally but is held against rotation relative to said bar, is a worm wheel 53 which has a swiveled connection with the bracket 43, as indicated at 54, whereby said bracket may rotate relative to said worm wheel but is constrained to move therewith longitudinally along the bar 11.

Carried by the bracket 40 is a worm 55 which meshes with the worm wheel 53. Accordingly, by rotatably adjusting said worm 55, the bracket 40 may be adjusted rotatably about the supporting bar 11 to adjust the guide element 24 to any desired angle between the vertical and the horizontal.

The supporting arm 11 is provided with rack teeth 56 and the worm wheel 53 has journaled therein a shaft 57 on which is fixed a pinion 58 which is in mesh with said rack teeth. Accordingly, by rotating said shaft 57 and its pinion 58, the entire unit B may be adjusted longitudinally along the supporting bar 11. The clamp screw 44 is, of course, loosened whenever it is desired to rotatably or longitudinally adjust the bracket 40 and the parts carried thereby, and may be tightened to maintain any adjustments made.

The tool driving motors may be either electric motors or motors that are driven by air or other fluid under pressure, or some of them may be electric motors and others may be fluid driven motors. Moreover, instead of the specific means described for effecting adjustments of the motor-carrying guide elements and the motors, any other suitable means for this purpose may be provided. As illustrative, Figs. 1, 2 and 3 of the drawings show one of the work head units, designated as B', as being equipped with an air driven motor designated as 25'. These figures further illustrate a simple clamp bracket 59 in which the arm 37' of the guide element 24' of said unit B' is rotatably and longitudinally adjustable, and another simple clamp bracket 43' by which the clamp bracket 59 is carried and by means of which the unit B is mounted on its supporting bar 11 for adjustments longitudinally therealong and rotatively with respect thereto.

In Figs. 1, 2 and 3 the machine is illustrated as being set up for boring all necessary holes in a chair leg prior to its assembly with other elements to make up a chair. Any suitable means may be employed to insure proper positioning of the chair leg relative to the fastening units C before it is clamped by said units, and the work heads are, of course, properly adjusted so that when their motors and tools are projected the desired holes will be bored in the leg at the proper locations. One of the work heads is illustrated as being mounted upon the rear of the lower pair of supporting bars 11 for forward projection of its motor to bore a hole in the front edge of the chair leg; four of the work heads are illustrated as being mounted upon the front of the lower

pair of the supporting bars 11 for upward projection of their motors to bore holes in the side of the chair leg, and another of the work heads (the work head B') is illustrated as being mounted upon the front of the upper pair of supporting bars 11 for rearward projection of its motor to bore a hole in the rear edge of the chair leg. Two other work heads also are illustrated, one as being mounted upon a transverse supporting bar 13 at one end of the machine and provided with a tool in the form of a dowel-forming chuck, and the other also as being mounted upon a transverse supporting bar at the other end of the machine and as being provided with a tool in the form of a circular cut-off saw. These two last mentioned units are not employed to perform any operations on the chair leg a, but are illustrated merely to show that they may be employed to perform dowel-forming and cut-off operations upon the ends of other pieces of work clamped by the work fastening units C. Obviously, two of the units provided with cut-off saws may be employed, one at each end of the machine or, alternatively, two of the units provided with dowel-forming chucks may be employed, one at each end of the machine. In fact, any desired combination and arrangement of the work heads may be employed to perform all required operations on any given piece of work clamped by the work fastening units C.

When the machine is set up for performing all required operations upon pieces of work all of which are alike, all of the various different tool driving motors are connected to a source of electric current or to a source of air or other operating fluid under pressure and are continuously operated. On the other hand, the motors may be projected simultaneously or in desired sequence depending upon whether all are free to be projected simultaneously or whether projection of any one might interfere with projection of any other of the same. To insure projection of the motors as well as projection of the work clamping elements at the proper times, a suitable valve, designated generally as 60, driven by an electric motor 61 or by any other suitable means, may be interposed between the source of fluid under pressure, represented by the pipe 62, and the hose or other conduits 63 leading to the different motor and tool projecting and work clamping cylinders.

The valve 60 and its driving motor 61 may conveniently be mounted upon a platform 64 at the upper, rear part of the machine supported upon suitable bracket arms 65 mounted upon the end plates 10, 10 of the machine, and the driving connection between said valve 60 and said motor 61 may include a suitable speed reduction unit 66 whereby said valve is driven at a suitable low speed.

The valve 60 may have, for example, three outlets, as shown, each connected to a separate manifold pipe 67, and the construction of said valve may be such that as it is driven it directs air or other fluid under pressure to the manifold pipes 67 successively. Any cylinder and piston units that are to be simultaneously operated may be connected to one of said manifold pipes, while any cylinder and piston units that are to be operated at different times may be connected to different of said manifold pipes. Thus, the work clamping cylinder and piston units may be connected to one manifold pipe 67 for operation in advance of the cylinder and piston units for advancing the tool driving motors, and

the latter cylinder and piston units may be connected to the other of said manifold pipes for operation simultaneously or in proper sequence, as may be necessary.

When the machine is in operation all of the tool driving motors are, as aforesaid, driven continuously and the work clamping and the tool driving motors are advanced and retracted at proper and regular intervals. First, the work clamping units are actuated to clamp a piece of work *a* to be operated upon; next the different tool driving motors are advanced either simultaneously or in desired sequence to cause their tools to perform their operations and then are retracted and remain retracted until the work clamping units are released. The piece of work *a* operated upon then is removed and a new piece of work is positioned to be clamped and operated upon, whereupon the clamping and work performing operations are repeated, all automatically. The speed of operation of the valve 60 may be varied in any suitable manner to vary the speed of operation of the machine which is, in turn, dependent upon the rapidity with which any given operator of the machine may supply and remove work pieces *a* to and from the work clamping units C.

Preferably the work-piece rests 16 are provided with suitable arms 68 to guide the work-pieces *a* during their supply to and removal from the machine so as to avoid the possibility of their contacting with and becoming marred by any given tool located in front of the work clamping means.

Each manifold pipe 67 may have as many outlet nipples 69 as desired with which may be connected by hose 63 to any desired cylinder and piston units, and said nipples may have normally closed valves to be opened by connection of the hose with the nipples in accordance with known practice so that air or other fluid is delivered through only those nipples with which hose are connected.

Conveniently, a panel 70 may be provided in front of the platform 64 to support one or more of the manifold pipes 67 and to have the nipples 69 extend therethrough for ready connection of hose therewith as well as to support electrical outlets 71 with which the cables 72 leading to the tool operating motors may be connected.

In any instance where a given motor or its tool is projected across the path of projection of another motor or its tool, means may be provided to insure against projection of the first mentioned motor and its tool unless the second mentioned motor and its tool are retracted, thereby to insure against collision and damage of the respective work heads. This means may comprise a normally closed valve 73 interposed in the hose leading to the cylinder and piston projection unit B of the first mentioned motor and mounted so as to be opened by retraction of the second mentioned motor. Thus, operating fluid cannot flow to the cylinder and piston unit of the first mentioned motor unless the second mentioned motor is retracted. Fig. 11 of the drawings illustrates the valve 73 as being mounted upon the cylinder of a motor projecting unit and as having a stem 74 to be engaged by the motor when the latter is retracted for the purpose of opening said valve. The valve itself may be of any suitable construction such that it closes when the motor is projected and is opened responsive to depression of its stem 74 by the motor 25.

From the foregoing description considered in connection with the accompanying drawings, it is believed that the construction and operation of the machine will be clearly understood and its advantages appreciated. It is desired to point out, however, that while only a single, specific structural embodiment of the invention has been illustrated and described, the same is readily capable of embodiment in specifically different structures within its spirit and scope as defined in the appended claims.

What is claimed is:

1. A machine of the character described comprising a frame including a rack bar, work fastening means, a gear wheel mounted on said rack bar for sliding adjustments therewith and non-rotation relative thereto, a bracket swiveled to said gear wheel for sliding movement therewith and for rotation relative thereto about the axis 15 of said rack bar, a pinion mounted on said gear wheel and in mesh with the rack of said rack bar for slidably adjusting said gear wheel and said bracket relative to said rack bar; a second gear wheel carried by said bracket and in mesh 20 with said first mentioned gear wheel for rotatively adjusting said bracket relative to said first mentioned gear wheel and said rack bar, a guide element mounted on said bracket for adjustment toward and away from the same, a motor 25 mounted on said guide element for projection and retraction relative thereto, and a tool driven by said motor for operation upon a piece of work fastened by said work fastening means.

2. A machine of the character described comprising a frame including a rack bar, work fastening means, a gear wheel mounted on said rack bar for sliding adjustments therewith and non-rotation relative thereto, a bracket swiveled to said gear wheel for sliding movement therewith 30 and for rotation relative thereto about the axis of said rack bar, a pinion mounted on said gear wheel and in mesh with the rack of said rack bar for slidably adjusting said gear wheel and said bracket relative to said rack bar; a second gear wheel carried by said bracket and in mesh 35 with said first mentioned gear wheel for rotatively adjusting said bracket relative to said first mentioned gear wheel and said rack bar, a guide element mounted on said bracket for rotative adjustments about an axis at right angles to the axis of said rack bar and also for adjustments toward and away from said bracket and said rack bar, a motor mounted on said guide element for projection and retraction relative thereto, 40 and a tool driven by said motor for operation upon a piece of work fastened by said work fastening means.

3. A machine of the character described comprising a frame including a supporting bar, work fastening means, a bracket mounted on said supporting bar for adjustments longitudinally and 45 rotatively relative thereto, said bracket including a housing extending at right angles to said supporting bar, a guide element, an arm rigid with 50 said guide element and mounted in said housing for adjustments longitudinally and rotatively relative thereto, a gear wheel on said arm and keyed thereto and mounted for rotation but non-longitudinal movement relative to said bracket, 55 a second gear wheel carried by said bracket and meshing with said first mentioned gear wheel for rotatively adjusting said arm and guide member relative to said bracket, a motor mounted on 60 said guide element for projection and retraction 65 relative thereto, and a tool driven by said motor 70 relative thereto, and a tool driven by said motor 75 relative thereto, and a tool driven by said motor

for operation upon a piece of work fastened by said work fastening means.

4. A machine of the character described comprising a frame including a supporting bar, work fastening means, a bracket mounted on said supporting bar for adjustments longitudinally and rotatively relative thereto, said bracket including a housing extending at right angles to said supporting bar, a guide element, an arm rigid with said guide element and mounted in said housing for adjustments longitudinally and rotatively relative thereto, a gear wheel on said arm and keyed thereto and mounted for rotation but non-longitudinal movement relative to said bracket, a second gear wheel carried by said bracket and meshing with said first mentioned gear wheel for rotatively adjusting said arm and guide member relative to said bracket, screw means for adjusting said arm longitudinally relative to said housing, a motor mounted on said guide element for projection and retraction relative thereto, and a tool driven by said motor for operation upon a piece of work fastened by said work fastening means.

5. In a machine of the character described, work fastening means, a first projectable and retractable motor, a second projectable and retractable motor, a tool driven by each motor for operation upon a piece of work fastened by said work fastening means, yieldable means tending constantly to retract each motor and its tool, a fluid-operated cylinder and piston unit for projecting each motor and its tool, the path of projection and retraction of one of said tools being disposed in the path of projection and retraction

of the other of said tools, fluid pressure supply conduits connected to said cylinder and piston units, and means to insure retraction of said first mentioned tool and its driving motor before said second mentioned tool and its driving motor may be projected, thereby to avoid collision and damage of said tools or motors, said last named means comprising a normally closed valve in the fluid pressure supply conduit of the second mentioned cylinder and piston unit mounted to be opened only by contact on retraction of said first mentioned motor with the stem of said valve.
